UNITED STATES PATENT OFFICE.

JULIUS BECKER, OF ESSEN-ON-THE-RUHR, GERMANY, ASSIGNOR TO FRIED. KRUPP AKTIENGESELLSCHAFT, OF ESSEN-ON-THE-RUHR, GERMANY.

GUN WITH PIVOT-MOUNT.

1,127,394.

Specification of Letters Patent.

Patented Feb. 9, 1915.

Application filed October 6, 1909. Serial No. 521,405.

To all whom it may concern:

Be it known that I, JULIUS BECKER, a subject of the Emperor of Germany, and a resident of Essen-on-the-Ruhr, Germany, have invented certain new and useful Improvements in Guns with Pivot-Mounts, of which the following is a specification.

The present invention relates to guns with pivot mounts and the object of the invention is to arrange and construct this type of guns in such a manner that, when out of use, the guns can be folded so as to require but small space in folded condition.

In the accompanying drawings, Figure 1 shows diagrammatically a side view of one embodiment of the invention and of some parts of a submarine boat; Fig. 2 is an end view of Fig. 1 partly in section; Fig. 3 is a top view of Fig. 1; and Fig. 4 is a view corresponding to that shown in Fig. 1 but showing another embodiment of the invention.

Reference will first be had to the embodiment shown in Figs. 1 to 3.

The pivot mount consists of the pivot column A and the pivot fork B which can turn about the axis of the pivot pin b^1 (Fig. 2) journaled in the column A. The gun barrel C is swingingly mounted in the fork B through the medium of the two horizontal trunnions c^1 . A shoulder-piece c^2 and a sighting device (not shown in the drawing) are removably secured on the gun barrel. The pivot column A has its lower end connected to the gun platform by means of a joint D in such a manner that the column can be folded into a horizontal position. The pivot fork B is curved toward the muzzle of the gun barrel C so that the gun barrel can be turned, with the muzzle directed downwardly, into a position parallel to the axis of the pivot pin b^1 as indicated in dotted lines in Fig. 1. Pivot forks constructed in a similar manner are known

per se. The joint D is located in a compartment E which is provided in the deck-superstructure of the submarine boat and which is adapted to receive the folded gun. The compartment E can be closed water-tight by means of a cover H (Figs. 1 and 2). A pipe (not shown) which can be shut off leads from the bottom of the compartment E to the water exterior and through this pipe

the water can be let out which enters the compartment E when the cover H is removed.

In the position of use of the gun the pivot column A can be secured in the vertical position by means of four rods F which are jointed to the gun platform.

When it is desired to dive with the boat or when, during the surface travel of the boat, the gun is not in use, the sighting device and the shoulder piece c^2 are first removed from the gun barrel; the rods F are then disconnected from the pivot column A and the gun barrel C is turned into the vertical position indicated in dotted lines in Fig. 1. The gun can then be folded into the compartment E in which it assumes the position indicated in dotted lines in Fig. 1. Finally the compartment E is closed by the cover H so that the gun is protected against the action of the sea-water. Furthermore, when the gun is in the folded position it does not present any resistance to the submerged travel of the boat.

In the embodiment shown in Fig. 4 the pivot fork B is curved toward the breech of the gun barrel C so that the gun barrel, when lying in the compartment E, is located above the pivot column A. The joint D is accordingly arranged directly over the bottom of the compartment E.

It is evident that the invention is not only applicable to guns mounted on submarine boats but it can be employed in all instances where it, for instance, is of importance that the gun, when not in use, should be concealed from view or protected from the effect of the weather. Furthermore, when there is sufficient available space in the compartment for receiving the folded gun, the pivot fork may be constructed in the usual manner. When the pivot column has been folded the gun barrel would then assume an inclined position relative to the column.

Having thus described the invention, what is claimed and desired to be secured by Letters Patent is:—

1. The combination with the gun platform having a compartment, of a pivot mount, a fork formed with forwardly projecting prongs, a gun mounted on the fork, a joint connecting the mount and the platform in such a manner that the gun can be folded.

horizontally within the compartment, stays for supporting the gun in position for firing and a closure for the compartment.

2. The combination with the gun platform 5 having a compartment, of a gun mount provided with forwardly projecting prongs, a gun pivotally mounted on the respective prongs and adapted to be folded in horizontal position within the compartment, and a closure for said compartment.

3. The combination with the gun platform having a compartment, of a pivoted gun mount having a joint, connecting it with said platform and stays secured to the platform for holding the mount rigid, a fork and a gun with horizontal trunnions mounted therein to have lateral training on the mount and adapted to be folded parallel therewith, said gun and the mount adapted 20 to be swung around said joint so as to fold horizontally within the compartment of the platform.

4. The combination with the gun platform, of a gun mount, a fork adapted to turn for lateral training relatively to the mount 360°, a gun with horizontal trunnions mounted in the fork, a permanent link connection between said gun mount and said platform allowing the gun and the mount to be folded 25 horizontally on the platform, and means for securing the mount in the firing position.

5. The combination with the gun platform,

of a gun mount, a fork adapted to turn for lateral training relatively to the mount 360°, a gun with horizontal trunnions mounted in the fork, a permanent link connection between said mount and said platform allowing the mount to be put down on the platform, means allowing the gun to be brought into horizontal position when the mount is put down on the platform and means for securing the mount in the firing position.

6. The combination with the gun platform having a compartment, of a gun mount, a fork adapted to turn for lateral training relatively to the mount 360°, a gun with horizontal trunnions mounted in the fork, a permanent link connection between said gun mount and said platform allowing the gun and the mount to be folded horizontally 30 within the compartment of the platform, said compartment having a depth approximately corresponding to the height of the gun and the gun mount when folded within the compartment, and means for securing the mount in the firing position.

The foregoing specification signed at Barmen, Germany, this 15th day of September, 1909.

JULIUS BECKER. [L. s.]

In presence of—

OTTO KÖNIG,

CHAS. J. WRIGHT.
